UNITED STATES PATENT OFFICE.

EZEKIEL J. WILSON, OF EAST GREENBUSH, NEW YORK, ASSIGNOR TO F. C. HUYCK & SONS, OF RENSSELAER, NEW YORK, A CORPORATION OF NEW YORK.

FULLING MILL.

Application filed April 30, 1923. Serial No. 635,794.

The invention relates to fulling mills for fulling fabric such, for instance, as endless felts designed for use in paper making machines.

5 It is the object of the invention to provide a construction by which the pressures and strains to which the fabric is subjected during the fulling may be accurately regulated to suit the character of the fabric being 10 operated upon or its condition at any stage of the fulling operation, and also to provide a construction by which the operator may determine the method best suited to secure the rapid and desired fulling of a fabric of 15 given design and character, and may thereafter repeat the same method of treatment in fulling like fabric, thereby reducing the length of time required for the fulling operation and also avoiding the delays incident to repeated removal and testing of the 20 fabric during the progress of the fulling.

To these ends the invention contemplates the provision in a fulling mill provided with main fulling rolls, the pressure of which 25 on the fabric may be adjusted, of means for measuring and indicating the pressure applied to the fabric by the rolls and also contemplates the provision of two throat posts preferably in the form of rolls which may 30 apply to the fabric drawn between them by the main rolls, a pressure which is also measured and indicated and may be adjusted as desired. The means for measuring and indicating the pressure applied by the 35 main rolls enables the operator to apply predetermined or known pressures to the fabric and to vary these pressures at such intervals and in such relation as experience shall demonstrate is best suited for the rapid and 40 desired fulling of the particular fabric being operated upon. The combination of the throat posts or rolls with the main rolls permits the lengthwise pull put on the fabric by the main rolls to be varied or ad- 45 justed as found desirable to insure the proper relative shrinkage in width and length during the fulling. By measuring and indicating this pressure, as well as the pressure of the main rolls, the best methods 50 of treatment for different fabrics may be determined and thereafter subsequently repeated for like fabrics and the rapidity and uniformity of the fulling thereby increased.

A machine embodying one form of the 55 invention is shown in the accompanying

drawings in which Fig. 1 is a right hand side elevation of the machine, Fig. 2 is a sectional elevation on line 2, Fig. 1, Fig. 3 is a partial plan view, and Fig. 4 is a partial front elevation.

The machine shown is provided with the usual casing 2, for containing and supporting the fabric passing to and from the devices which work thereon. The machine is also provided with a pair of main fulling rolls comprising the lower roll 4 carried on the end of a shaft 6 mounted in fixed bearings and an upper roll 8 mounted for movement toward and from the lower roll. The roll 8 is provided at its ends with trunnions 10 carried in bearings 12 mounted to slide vertically between fixed guiding brackets 14. The means for forcing the roll 8 toward the roll 4 with a regulated or adjustable pressure comprises a lever in the form of a frame provided with two side bars 16 connected by a cross rod 18 and cross bars, one of which is indicated at 20 in Fig. 3. The forward end of the lever is connected with the bearings 12 by thrust links 22, the lower ends of which are pivoted to the bearings, and the upper ends of which are pivoted on the cross rod 18. The side bars of the lever are pivoted at 24 upon the frame of the machine and extend rearwardly and form guide arms engaging the outer surfaces of vertical guide bars 26. Near their rear ends the bars 16 are provided with transverse bearing blocks 28 which are engaged by the ends of a heavy multiple leaf spring 30. The center of the spring is secured in a head 32 which is connected through a chain 34 with the hoist 36 by which the spring may be adjusted to vary the pressure applied thereby to the lever and through it to the upper fulling roll.

The means for measuring and indicating the pressure applied to the fabric by the main rolls is included in the connection between the hoist 36 and the spring 30 through which the spring is adjusted and comprises the elliptical spring link 38, the upper end of which is connected to the chain 34 and the lower end of which is connected with the head 32 at the center of the spring. Variation in the pull of the spring 30 on the spring link 38 will cause the sides of the link to move toward or from each other and this movement causes a finger 40 to

move over graduations on the scale 42 and thus measure and indicate the pressure exerted by the spring on the lever bars 16. The scale may be calibrated to indicate the pressure applied by the main rolls to the fabric. The head 32 may be guided by a rod 44 which slides through a guide 46 and has its upper end secured to the head.

The fabric supported within the casing 2 passes up over the horizontal guide rolls 48 and from the upper roll passes between two vertical throat posts 50 which are spaced for the passage of the fabric between them and are arranged directly in front of the main rolls. The throat posts are preferably in the form of rolls, the upper ends of which are journaled in the rear ends of supporting levers 52. The levers are pivotally supported on a cross bar 54 and are connected by gear segments 56 so that they move simultaneously and in unison toward and from each other. The forward ends of the supporting levers 52 are connected by pin and slot connections 58 with the inner ends of two levers 60, the outer ends of which are connected by an adjustable spring link connection through which separation of the throat rolls by the fabric passing between them may be resisted. The spring link connection comprises a screw-threaded rod 62 passing through one of the levers 60, a measuring and indicating device 64 connected with the end of the other lever and a coiled spring 66 connecting this device with the rod. The screw-threaded outer end of the rod 62 is engaged by the screw-threaded hub of a pulley 68 which may be rotated to adjust the spring link connection between the levers through an operating chain 70 arranged within convenient reach of the operator. The measuring and indicating device is the same in construction as that for measuring and indicating the pressure applied by the main rolls and comprises the elliptical spring link, one side of which carries the graduated dial plate 72 and indicating finger 74, and the other side of which carries the rack 76 engaging a pinion on the pivot of the indicating finger.

By adjustment of the pulley 68 the throat rolls may be adjusted to apply any desired pressure to the fabric drawn between them by the main rolls and to offer any desired resistance to separation by the fabric passing between them. This pressure or resistance will be measured or indicated by the finger 74 and graduated dial 72, and therefore the throat rolls may be adjusted to apply a known or predetermined pressure to the fabric. This pressure will be substantially uniform since any slight movement of the throat rolls toward or from each other during the passage of the fabric between them will be taken up by the coiled spring 66 without material variation in the pressure.

The fabric drawn through the throat rolls is thrust by the main rolls through a trough or spout comprising the base board 78, side boards 80 and pivoted vertically movable evening board 82 which may be of a construction such as is usually employed in fulling mills of the present type. The right hand side board 80 is supported by hinged straps indicated at 84 so that it may be swung up to permit the endless roped felt or other fabric to be introduced laterally into the trough and between the main rolls. To facilitate the introduction of the fabric the right hand throat roll may also be mounted so that it may be swung up for the introduction of the fabric and then returned to normal position after the fabric has been introduced. For this purpose the right hand lever 52 may be made in two sections pivoted together as indicated at 86 in Fig. 3 and locked in normal position by a bolt 88 indicated in Fig. 1. For convenience in disengaging and re-engaging the bolt its outer end may be bent laterally to engage a slot in the pivoted operating lever 90 arranged at the side of the machine frame.

By the construction shown and described the operator may readily adjust the pressure applied to the fabric by the main fulling roll and the pressure applied to the fabric by the throat rolls to subject the fabric to known pressures for any desired periods and to subject the fabric to that method of treatment which experience has demonstrated will most quickly secure the desired fulling and the proper relative shrinkage in length and width. If upon removing and measuring the fabric, as is customary at intervals during the fulling operation, it is found that the shrinkage in length is too rapid as compared with the shrinkage in width the pressure of the throat rolls may be increased so that the tension or pull on the fabric between the throat rolls and main rolls will be increased with a tendency to decrease the shrinkage in length. If, on the other hand, it is found that the shrinkage in length is too slow as compared with the shrinkage in width the pressure of the throat rolls may be decreased or may be removed so that the rolls act merely as guide rolls, or in the case of excessive variation the evening board 82 may be adjusted so that the throat will offer greater resistance to the passage of the fabric pushed therethrough by the main rolls. The pressure of the main rolls may also be adjusted in any manner which experience has shown is desirable and to apply a known pressure. Fabrics may thus be subjected to known and uniform treatment and to that treatment which experience may demonstrate will give the best results.

While it is preferred to employ substantially the construction and arrangement of

parts shown and described it will be understood that this construction and arrangement is not essential to the broader features of the invention and may be varied or modified 5 as found desirable or best suited to the construction and the arrangement of the parts of the machine in which such features may be embodied.

I claim—

1. In a fulling mill the combination of a pair of main fulling rolls, the upper one of which is carried in vertically movable bearings, a lever, the forward end of which is connected with the bearings, a spring acting 15 on the rear end of the lever, and devices for adjusting the force of the spring including a measuring and indicating device subjected to the force of the spring.

2. In a fulling mill the combination of a 20 pair of main fulling rolls, the upper one of which is carried in vertically movable bearings, a lever, the forward end of which is connected with the bearings, and the rear end of which is provided with two spaced 25 arms, a leaf spring, the ends of which act on the arms, an adjustable support for the center of the spring, means for applying an adjusted pull to the support, and a measuring and indicating device through which the 30 pull is applied.

3. In a fulling mill the combination of a 35 pair of main fulling rolls, a pair of throat posts mounted to yield as the fabric is drawn between them by the main rolls, a spring connected to resist the yielding of the posts, and means for measuring and indicating the resistance offered by the spring.

4. In a fulling mill the combination of a 40 pair of main fulling rolls, a pair of throat posts between which the fabric is drawn by the main rolls, means for maintaining the posts in parallel relation and for pressing them yieldingly against the fabric adjustable to vary the pressure on the fabric, and 45 means for measuring and indicating said pressure.

5. In a fulling mill the combination of a

pair of main fulling rolls, a pair of throat posts mounted to yield as the fabric is drawn between them by the main rolls, a spring 50 connected to resist the yielding of the posts, means for adjusting the spring to vary the resistance offered thereby, and means for measuring and indicating the resistance offered by the spring. 55

6. In a fulling mill the combination of a pair of main fulling rolls, a pair of throat posts between which the fabric is drawn by the main rolls, adjustable means for pressing the throat posts yieldingly against the fabric including a device for measuring and indicating the pressure applied by the posts. 60

7. In a fulling mill the combination of a pair of main fulling rolls, two throat posts between which the fabric is drawn by the 65 main rolls, two pivoted supports for the posts connected to move simultaneously in opposite directions, levers connected with the supports, an adjustable link connection between the ends of the levers comprising a 70 spring and a measuring and indicating device.

8. In a fulling mill the combination of a pair of horizontal main fulling rolls, a pair 75 of vertical throat rolls, supports for the throat rolls movable to and from each other, one of said supports comprising two sections pivotally connected to permit the corresponding roll to be swung up so that the fabric may be passed horizontally into position between the two sets of rolls, and means for latching the two sections together. 80

9. In a fulling mill the combination of a pair of main fulling rolls, the upper one of which is carried in vertically movable bearings, a lever the forward end of which is connected with the bearings and the rear end of which is provided with two spaced arms, a leaf spring the ends of which act on the arms, an adjustable support for the center of the spring, and means for adjusting the support. 85 90
